FILE HOLDING DEVICE

Fritz Albert Eix, Los Angeles, Calif.

Application November 14, 1939, Serial No. 304,369

5 Claims. (Cl. 29—80)

This invention relates to a holding device for files used by mechanics for dressing down irregular metal surfaces and for other purposes.

An object of the invention is to provide a superior handle construction or supporting frame for a file of the elongated, usually flat type, which mechanics have generally hitherto operated by holding it directly in the hands or else by means of a handle having a socket into which one end 10 of the file is inserted; the file holding frame provided by this invention being more comfortable to the hands of the mechanic and being a more convenient means for operating the file. Also said file supporting frame affords an improved means for protecting the hands of the 15 mechanic from being injured in case the file accidentally breaks during use.

Another object of the invention is to provide a file holding frame which carries, in an improved manner, a resilient backing strip against which the file abuts, said frame being adjustable in such a way as to bow said strip in either direction so as to present either a concave working face or a convex working face of a file of the 25 slightly bendable type to the material being operated upon thereby. This feature of the invention enables the workman to apply the file more effectively to concave surfaces or to convex surfaces, as may be necessary in finishing off the 30 irregular surfaces of automobile bodies or other objects to which the tool is being applied.

Still another object of the invention is to provide a file holding frame which is constructed in a superior manner with a view to withstanding more satisfactorily the stresses put upon the tool from the handle portion thereof when being used. With this end in view the handle is disposed in a novel relation to the adjacent portions of the file supporting frame.

Other objects, advantages and features of invention will hereinafter appear.

Referring to the accompanying drawing, which illustrates what is at present deemed to be a preferred embodiment of the invention,

Fig. 1 is a side view of the device, parts thereof being shown in vertical mid-section and other parts in elevation.

Fig. 2 is a bottom plan view of the tool.

Fig. 3 is a sectional view thereof on line 3—3 of Fig. 1.

Fig. 4 is a sectional view thereof on line 4—4 of Fig. 1.

Referring in detail to the drawing, the file holding frame provided by this invention comprises a handle member 7 which is desirably

shaped similarly to the conventional saw handle, a head member 8, a bridge member 9 and a turn-buckle means 10. Said bridge member 9 is preferably of resilient metal, and of a strap shape, as shown. The means 10 may be defined as a rotatable adjusting rod which has a screw thread portion 11 operatively related to the head member 8 to apply thereto a traction or an expulsive force in relation to the handle member 7.

With the threaded rod portion 11 cooperates 10 an elongated nut or internally threaded sleeve 12 swingably mounted by means of a pivot pin 13 which interiorly spans the upper portion of the hollow head 8, said pivot pin being carried by apertured portions of the head 8, and being 15 double headed to keep it in place.

At its opposite end said rod 10 is swiveled to the upper portion of the hollow handle member 7 by means of a swingable sleeve 15 having a diametrically reduced part 16 within which the 20 adjacent end portion of the rod is turnably fitted. Said rod has an upset extremity 18 which contacts a washer 18w that engages the inner end of the part 16, to exert traction. The sleeve 15 is swiveled to the handle 7 by means of a 25 cross pin 19. A milled collar 20 fixed to the rod 10 provides for its manual rotation and abuts against the sleeve 16 to give the aforesaid expulsive force.

In the drawing is shown an elongated flat file 30 25 of the resilient type which is provided with a countersunk aperture near each end to receive the screws 26 and 27 whereby said file is secured to the device in a flatwise or abutting position in relation to the outer face of the bridge member 9.

Through the flat base 7b of the handle member 7 is an aperture which aligns with the aperture of a plate or anchor strip 30 welded to the upper surface of said base 7b into which said screw 26 screws. Likewise the head member 8 has an apertured flat base portion 8b through which extends screw 27 which screws into a plate or anchor member 31. One end portion of the bridge member 9 is permanently secured to the 45 base portion of the handle member 7 by means of two screws 9a which extend through said bridge member and are secured into sockets provided for them in the attached part 30. The opposite end portion of said bridge member is 50 slotted at 9b to allow for its adjustment in relation to the screw 27.

The handle member 7 and the head 8 are each hollow and each consists of two die formed sheet metal halves, the line of cleavage being along the 55

mid-width of the tool. The plates or anchor members 30 and 31 are respectively shown secured to the basal portions of the members 7 and 8 by means of welds 30w and 31w. As is to be seen from the drawing, these welds are both confined to one side of the median line of the device and hence said anchor members, after being welded in place, do not interfere with the assembling of the two halves of the end portions 10 of the tool. These halves are shown secured together by the rivets 35 within the handle member 7, and rivets 36 within the head member 8. The pivot pins or rivets 13 and 19 also aid in uniting the two halves of the members 7 and 8. 15 Six rivets are shown. The twelve apertures for these rivets are all desirably formed by punching holes in inward directions and leaving around the inner edge of each hole a burr or lip 14 which gives added strength to the material adjacent to 20 the halves.

In the manufacture of the tool, the plate or anchor members 30 and 31 are welded in place in the proper positions before the two halves of each member (7 or 8) are secured together. 25 Then, after the two halves of the members 7 and 8 have been secured together by the various rivets which have been mentioned, the holes to receive the screws 26 and 27 are drilled through the basal portions of the members 7 and 8 in 30 axial alignment with said nuts.

The handle member 7 has a spacious opening 37 to provide an ample working clearance around the sleeve 15 and adjacent part of the rod 10, and the head 8 likewise has a roomy opening 38 35 to provide a working clearance around said rod, hence said handle and head may be varied greatly in their relative angular positions, affected by the rotation of said rod.

Describing in further detail the milled collar 40 20 and parts adjacent to it, the rod 10 has a diametrically reduced end portion 10x which enters the sleeve 15 and which, as has been stated, has an upset end 18 to exert traction against the washer 18w. The collar 20 is secured to the rod 45 10 in any approved manner, for example by welds 20w. The face of the collar 20 which is directed towards the handle member 7 affords a broad compression bearing surface against the end of sleeve 15 thereby reducing wear.

50 The adjusting rod 10 is connected with the top portion of the handle 7 at a sufficient distance from the base of said handle to permit the entire hand of the operator to grasp the handle below said rod. Efficient operation of the tool is thus 55 provided for.

I claim:

1. A file holding device of the kind described including a hollow handle member formed in two halves each of which has a flat basal portion, a strap-like bridge piece positioned in a flatwise abutting manner under said basal portions, there being aligned openings through said bridge piece and the two-part basal portion of said handle member to receive an attaching screw, and a plate having a screw threaded aperture for such screw, said plate being secured within the basal portion of said handle by welding located only in one half thereof.

2. In a file holding device of the kind described having a handle member and a head member, a file holding strip connected with the basal portions of said members a manually rotatable rod connecting the upper portions of said members with each other, one end portion of

said rod having a screw threaded relation to one of said members whereby, when rotated in opposite directions, it exerts pressure thereagainst and traction thereupon, and a sleeve into which the opposite end of said rod is swivelled, said sleeve being mounted upon the member at that end of the rod, and said rod carrying a collar to facilitate its manual rotation, said collar abutting against the end of said sleeve to apply pressure thereagainst.

3. A file holding device comprising an upstanding handle member at one end and a head member at the opposite end, a strip of resilient metal one end portion of which is secured to the base portion of said handle member and the opposite end portion of which is secured to the base portion of said head member, means to secure a file to the device in an underlying abutting relation to said strip, and a rotatable rod connecting the upper portion of said handle member with the upper portion of said head member, said handle being manually grippable by the operator below the connection of said rod therewith, one of said members carrying a part where-with said rod has a screwthreaded relation and the other of said members carrying a part to which said rod is swiveled in a manner affording both traction thereupon and extension thereof, said strip of resilient metal being longitudinally slotted at one end and the securing means at 30 that end thereof extending through said slot.

4. A file holding device comprising a hollow, upstanding handle member at one end and a head member at the opposite end, a strip of resilient metal one end portion of which is secured to the base portion of said handle member and the opposite end portion of which is secured to the base portion of said head member, means to secure a file to the device in an underlying abutting relation to said strip, and a rotatable rod connecting the upper portion of said handle member with the upper portion of said head member, said hollow handle member having in its upper portion an opening in the side thereof which is directed toward the opposite end of the tool, a swivel member within the upper portion of said handle member, and a pin extending across the upper part of the space within said handle member and swingably supporting said swivel member, a portion of the latter member projecting through the aforesaid opening, said rod being rotatably attached to said projecting portion of said swivel member, the opposite end portion of said rod having a screw threaded connection with the aforesaid head member to force the upper portions of said head member and handle member toward and away from each other.

5. A file holding device of the kind described including a hollow handle member formed in two halves each of which has a flat basal portion, a strap-like bridge piece positioned in a flatwise abutting manner under said basal portions, there being aligned openings through said bridge piece and the two-part basal portion of said handle member to receive an attaching screw, and a plate having a screw threaded aperture for such screw, said plate being secured within the basal portion of said handle by welding located only in one half thereof, said plate also having screw threaded apertures to receive attaching screws for said bridge piece.
